CLAIM

I claim, the ornamental design for a gemstone, as shown and described.

DESCRIPTION

The file of this patent contains at least one photograph executed in color. Copies of this patent with color photograph(s) will be provided by the Office upon request and payment of the necessary fee.

FIG. 1 is a perspective view of a first embodiment of a gemstone, showing my new design;

FIG. 2 is a bottom view thereof;

FIG. 3 is a top view thereof;

FIG. 4 is a left side view thereof, the opposite side view being a mirror image thereof;

FIG. 5 is a rear view thereof;

FIG. 6 is a front view thereof;

FIG. 7 is a perspective view of a second embodiment of the gemstone, showing my new design;

FIG. 8 is a front view thereof;

FIG. 9 is a rear view thereof;

FIG. 10 is a bottom view thereof;

FIG. 11 is a left side view thereof, the opposite side view being a mirror image thereof;

FIG. 12 is a top view thereof;

FIG. 13 is a perspective view of a third embodiment of the gemstone, showing my new design;

FIG. 14 is a left side view thereof, the opposite side view being a mirror image thereof;

FIG. 15 is a rear view thereof;

FIG. 16 is a front view thereof;

FIG. 17 is a bottom view thereof; and,

FIG. 18 is a top view thereof.
